UNITED STATES PATENT OFFICE.

JOHN C. MILLER, OF WATERBURY, CONNECTICUT, ASSIGNOR TO THE MATTHEWS & WILLARD MANUFACTURING COMPANY, OF SAME PLACE.

DESIGN FOR A TABLE-LEG.

SPECIFICATION forming part of Design No. 24,325, dated May 21, 1895.

Application filed April 22, 1895. Serial No. 546,770. Term of patent 3½ years.

To all whom it may concern:

Be it known that I, JOHN C. MILLER, of Waterbury, in the county of New Haven and State of Connecticut, have invented a new Design for a Table-Leg; and I do hereby declare the following, when taken in connection with the accompanying drawing and the letters of reference marked thereon, to be a full, clear, and exact description of the same, and which said drawing constitutes part of this specification, and represents a side view of a table-leg embodying my design.

This invention relates to a design for a table-leg, and the design consists in the configuration and ornamentation as shown in the accompanying illustration.

My newly designed table-leg, which I will describe from its upper end downward, comprises a short stem A, merging at its lower end into the upper end of a long scroll B, the convex side of which faces outward, and the lower end of which merges into the upper end of a long double scroll C, the upper main por-

tion of which has its convex side outward. The lower end of this double scroll curves inward, and merges into a rectangular die or ornament D, located at the upper end of a long scroll E, the convex face of which is outward, and which terminates at its lower end in an outwardly turned scroll shaped foot F.

The several members of the design are elaborately ornamented with leaves and beads, while the scrolls are also ornamented with flying or detached leaves G and sprays H, all as shown in the accompanying illustration.

I claim—

The design for a table-leg as herein shown and described.

In testimony whereof I have signed this specification in the presence of two subscribing witnesses.

JOHN C. MILLER.
